UNITED STATES PATENT OFFICE.

SAYRES N. LENNON, OF HURON, OHIO, ASSIGNOR OF ONE-HALF TO ADDISON H. WINCHELL, OF SAME PLACE.

END-GATE FOR WAGONS.

SPECIFICATION forming part of Letters Patent No. 393,016, dated November 20, 1888.

Application filed June 5, 1888. Serial No. 276,111. (No model.)

To all whom it may concern:

Be it known that I, SAYRES N. LENNON, a citizen of the United States, residing at Huron, in the county of Erie and State of Ohio, have 5 invented new and useful Improvements in End-Gates for Vehicle-Bodies, of which the following is a specification.

My invention relates to improvements in end-gates for vehicle-bodies, having for its object to provide simple and strong means for connecting the same to the sides of the wagon and for locking it in its closed position; and it consists in a certain novel construction and combination of devices, fully set forth herein- 15 after in connection with the accompanying drawings, wherein—

Figure 1 is a perspective view of an end-gate embodying my improvements and applied to a vehicle-body. Fig. 2 is a longitudinal sectional view taken through one end of the gate and the adjacent side, to show the construction and arrangement of the parts. Fig. 3 is a plan view of the same. Fig. 4 is a detail view of the headed stud. Fig. 5 is a similar view 25 of the casting or socket-plate.

Referring to the drawings, A designates the end-gate, which is mounted between the side-boards B, and bears at its lower edge on the bottom board, B'. A longitudinally-slotted 30 plate, C, is arranged on the bottom board under the center of the end-gate, and on a suitable wear-plate, D, which is affixed to the end-gate near its lower edge, is mounted the cam-plate E, having a handle, e. This cam is 35 adapted to be engaged in the slot in the plate C when the end-gate is in its closed position.

F represent castings or socket-plates, which are affixed to the upper corners of the end-gate over recesses formed therein, and are 40 provided with ears f, which are secured, respectively, on opposite sides of the end-gate. These castings or socket-plates form, in connection with the recesses, the sockets G G, and H designates vertical slots, which are 45 formed in the ends of the castings and communicate with the said sockets, and the lower ends of the slots form bearings for the studs I, which are arranged in the side-boards of the vehicle.

K represents a vertical strap, which is secured to the outer side of the side-board, and

is provided near its upper end with a squared aperture, k, and L designates a socket, which is affixed to or formed integral with the inner side of the said strap, and is provided with a 55 square bore, l, registering with an aperture, k, and tapered toward its outer end. The stud is provided with a tapered shank, M, which is square in section, and is fitted in the bore of the socket, and is threaded at its outer 60 end to receive a nut, m. The inner ends of the studs are provided with the laterally-extending heads N, which operate in the sockets G on either side of the slots H, and when the end-gate reaches its closed position these heads 65 bear against the shoulders O O, which are formed in the sockets. The object of the said shoulders is to prevent the heads of the studs from passing out of the sockets as the end-gate approaches its vertical position, and before the lower edge of the gate bears on the bottom of the body. When the end-gate is turned with its lower edge up, the gate may be raised vertically, and the heads on the ends of the studs will pass freely out of engagement 70 with the sockets G, and to prevent the head from passing out of the socket while the gate is in an intermediate position, or before it has reached its raised position, the free ends of the heads of the studs are provided with lips 75 P, (parallel with the shanks of the studs,) which engage inwardly-extending flanges Q at the lower ends of the slots H. Thus the end-gate may be freely swung on its pivoting-studs without danger of being accidentally detached, 80 and when it is desired to remove it it is readily and quickly accomplished in the manner above 85 described.

Having thus described the invention, I claim—

1. The end-gate having sockets at its upper corners, and a cam pivoted to the same near its lower edge, in combination with the studs arranged on the sides of the vehicle and engaging the sockets, and the slotted plate on 95 the bottom of the vehicle adapted to be engaged by the said cam, substantially as specified.

2. In an end-gate, the castings or socket-plates affixed thereto and having sockets there- 100 in, and vertical slots communicating with the sockets, in combination with the studs affixed

to the vehicle and provided with heads engaging the said sockets, substantially as specified.

3. In an end-gate, the castings or socket-
5 plates affixed thereto and having vertical slots
in their outer ends communicating with the
sockets, and the shoulders O in the sockets, in
combination with the studs on the vehicle-
body having laterally-extending heads oper-
10 ating in the sockets and adapted to engage the
said shoulder therein, substantially as speci-
fied.

4. In an end-gate, the castings or socket-
15 plates affixed thereto and having the vertical
slots H, the shoulders O, and inwardly-extend-
ing flanges Q, in combination with the sta-
tionary studs having lateral heads provided
with lips at their extremities, substantially as
specified.

20 5. In an end-gate, the castings or socket-
plates affixed thereto, in combination with the
studs having heads to engage the sockets, and
provided with squared shanks mounted in
squared sockets in the side-boards, substan-
25 tially as specified.

6. In an end-gate, the castings or socket-
plates affixed thereto, in combination with the

straps affixed to the sides of the vehicle-body,
the integral sockets extending through the
side and provided with a squared or angular 30
bore, the studs adapted to engage the sockets
and provided with squared or angular shanks
fitting in the bores of the said sockets, and the
nuts engaging the outer ends of the shanks,
substantially as specified.

35 7. In an end-gate, the castings or socket-
plates affixed thereto, in combination with the
sockets L, arranged in the sides of a vehicle-
body and having squared or angular bores
tapered toward their outer ends, the headed 40
studs engaging the sockets in the castings or
socket-plates, and provided with squared or
angular shanks tapered toward their outer
ends and fitting in the bores of the sockets L,
and the nuts engaging the outer ends of the 45
shanks, substantially as and for the purpose
specified.

In testimony that I claim the foregoing as my
own I have hereto affixed my signature in pres-
ence of two witnesses.

SAYRES N. LENNON.
